UNITED STATES PATENT OFFICE.

WILLIAM MASTERS, OF KANSAS CITY, MISSOURI.

STOVE OR FURNACE.

SPECIFICATION forming part of Letters Patent No. 274,130, dated March 20, 1883.

Application filed September 11, 1882. (No model.)

To all whom it may concern:

Be it known that I, WILLIAM MASTERS, residing at Kansas City, county of Jackson, State of Missouri, have invented certain new and useful Improvements in Stoves or Furnaces, of which the following I do hereby declare to be a full, clear, and exact description.

The invention consists in the combination, with a stove or furnace, of a perforated and independent hollow air-conduit located between the fuel and combustion chambers of the stove or furnace, and co-operating to effect the more perfect combustion of the gases and vapors distilled from the fuel charges, all as hereinafter set forth, and more distinctly defined in claims.

In the accompanying drawings, Figures 1, 2, 3, and 4 represent in vertical central section, parts being in perspective, a stove of ordinary construction having the hollow perforated air-conduit applied thereto. Figs. 5, 6, 7, and 8 show this air-conduit detached, the several types of conduit being applied to the stoves illustrated in Figs. 1, 2, 3, and 4, respectively. Fig. 9 is a front view of the joint by which the conduit is attached to the walls of the stove.

Located between what may be termed, for convenience, the lower or fuel chamber, A, and the upper or final combustion chamber, A', of a stove or furnace of usual construction is an independent hollow casing, C, which extends around the interior of the stove or furnace, but entirely separate from the walls thereof, so as to be readily removed and replaced when desired, and in position to be subjected to the play of the flame and hot gases about and upon its entire surface. The casing C has a large central opening, which, in conjunction with the spaces between said conduit and the inner casing of the stove or furnace, affords free egress for the vapors, gases, and combustion products from the lower chamber, A, to final-combustion chamber A', at the same time that these several products in their passage impart their heat in a measure to the air circulating within the conduit, so as to bring it into condition better fitted for union therewith when finally discharged into and among them. Perforations 50 in casing C admit air in numerous fine jets from the interior of said conduit into and

among the hot gases and vapors as they escape, effecting by this fresh supply of oxygen the more perfect combustion of the gases, so that the heating capacity of the same in burning is enhanced and the deposit of soot in flues or passages very materially reduced.

A perforated cross pipe, as at C', may join opposite parts of the conduit, serving, by reason of its position, to break the currents of gas and to still further distribute the air among the highly-heated vapors and gaseous products. The expanded combustion-chamber A', located, as shown, with respect to the air-conduit, enables the gases and vapors to freely expand at the moment of receiving fresh accessions of air, so that the ignition and burning thereof occurs under conditions most favorable to complete success.

The air-conduit C has short tubes c, extending from it to the inner walls of the stove, where they receive the tubular portion d of the joints D, which project through the holes of the stove or furnace casing, the flanged faces of said joints D being bolted to the stove-casing, and thus easily loosened at pleasure. By withdrawing the joints D a suitable distance the air-conduit C, being no longer sustained, can be readily removed from the stove and replaced. The removal may be accomplished either by taking off the top plate of the stove, as at a, Fig. 4, or the heating-drum A², as in Fig. 1; or, if the size and shape of conduit and stove will not admit of these expedients, then by lifting up the main casing, as at A³, Fig. 1, the conduit 85 may be easily taken out.

To govern the supply of air to the conduit and thence to the stove, dampers d³ are placed in joints D, so as to be readily removed at will of the attendant.

It is not new in the art to introduce a supplemental air-supply above the fuel in the fire-bowl to more effectually burn the hot gases and distilling vapors; but in one class of devices the air-conduit, or, more properly, the air-chamber, is an integral part of the stove, costly to make and difficult to replace. In some instances, though the air-conduit may in certain sense be independent, it is united with a perforated fire-pot in relation wholly different from the present invention and without means for the quick and easy replacement of defect-

ive conduits, as contemplated herein. Again, an air-conduit made up in part of the top wall of the stove and not wholly separate and distinct, as in present case, has been located above the fuel-space; but there is no combustion-chamber in said form to permit free expansion of the gases, so that there is no chance for that perfect burning of the gases and vapors which is accomplished by the present invention. The tubular joint for sustaining the conduit in position is convenient for the purpose, but has heretofore been used in similar relation, and is not claimed of itself.

Having thus described the invention, what I claim as new, and desire to secure by Letters Patent, is—

1. The combination, in a stove or furnace, of a perforated air-conduit provided with short lateral extensions which communicate with the outer casing of the stove, said conduit being

located between the fuel and final-combustion chambers and entirely separated from the wall of the stove or furnace, substantially as and for the purpose set forth.

2. The combination, with a stove or furnace, of a perforated air-conduit located between the fuel and final-combustion chambers and entirely separated from the walls of the stove, said air-conduit being provided with short lateral extensions which are united with tubular joints to sustain said conduit in position, substantially as described.

3. In a stove or furnace, a perforated air-conduit, C, having a cross-pipe, C', substantially as set forth.

WILLIAM MASTERS.
